CLAIM

The ornamental design for a mammography system, as shown and described.

DESCRIPTION

FIG. 1 is a front and right perspective view of a mammography system;

FIG. 2 is a top, front, and left perspective view thereof shown in a tilted portion;

FIG. 3 is a top and front perspective view thereof shown in a tilted portion;

FIG. 4 is a front view thereof;

FIG. 5 is a top plan view thereof;

FIG. 6 is a right side view thereof; and,

FIG. 7 is a left side view thereof.

The broken lines in the drawing views represent unclaimed portions of the mammography system and form no part of the claimed design.
